UNITED STATES PATENT OFFICE.

JOHN HERMAN, OF LOS ANGELES, CALIFORNIA.

PNEUMATIC SCREEN.

Application filed June 1, 1922. Serial No. 565,052.

To all whom it may concern:

Be it known that I, JOHN HERMAN, a citizen of the United States, residing at Los Angeles, in the county of Los Angeles and 5 State of California, have invented new and useful Improvements in Pneumatic Screens, of which the following is a specification.

This invention relates to pneumatic screens and has for its object to provide a 10 screen of economical construction and cost of operation and which will be efficient, especially, for the separation of finely ground or other material, such, for instance, as of one hundred mesh fineness.

15 An object is to provide an improved screening means and to provide for the direction of the material to be screened at an angle of substantially ninety degrees to the screening surface. A further object is 20 to provide a construction in which the material to be screened will be sustained while it is repeatedly directed toward the screening area.

An important object is to provide means 25 for effecting the removal of the oversize portion of material which is held against the screen by air pressure, and to accomplish the removal by the change of the effective pressures of air upon the oversize material.

30 Another object is to provide an apparatus in which there is presented a very large area of screen in proportion to the area of cross section of the draft chamber.

A further object is to provide a method 35 and apparatus whereby the same may be practiced for the efficient pneumatic screening of fine materials.

An embodiment of the invention is described in the following specification and 40 illustrated in the accompanying drawings, in which,

Fig. 1 is a front elevation of the machine, parts of which are broken away to illustrate interior construction.

45 Fig. 2 is a side elevation of the machine with a feeding conveyor illustrated partly in section.

Fig. 3 is a vertical section through the apparatus from front to rear.

50 Fig. 4 is a plan and partial section of the machine.

Fig. 5 is a detail sectional view showing 55 diagrammatically the screening and draft apparatus and indicating the modes of action thereof.

In its preferred embodiment the machine

includes a suitable base 2 and frame structure, which latter may consist of upwardly and forwardly extended side frame members 3 suitably spaced in parallel position 60 and carrying at the upper portion a separating chamber or box which includes a top plate 4 and a bottom plate 5 angularly disposed with respect to the base 2 and to the front of which plates is secured a suitable 65 and, preferably, removable front panel 6 which may be fastened as by means of a flanged frame 7 secured by bolts to the contiguous frame members.

At the ends of the machine there are suitably journaled oblique shafts 9 and 10 respectively carrying drums 11 and 12, the latter preferably being of a spring roller type so as to automatically return in one direction to wind up a screening medium 75 such as a sheet of fabric 13 appropriately attached to winding curtains 14 fastened to the drums 11 and 12.

Means are provided for intermittently drawing or pulling the screen member 13 80 from the spring drum 12 transversely to and fro within the separating chamber behind the front panel 6. The screening member 13 is arranged in an inclined position upwardly and forwardly and parallel to the front panel 85 6 and passes through guide slots 15 in the end walls or frame members 3. To secure a reciprocating movement of the screen member 13 one of the shafts, as shaft 9, is provided with a crank or disc element 16 to 90 which is connected a link 17, this in turn being attached to a crank 18 secured on the end of an upwardly inclining driving shaft 19 provided in suitable bearings 20 supported on the side members of the frame. 95

The crank shaft 19 has at its lower end a gear 21 of the bevel type engaging a complementary beveled gear 22 which is secured on a countershaft 23 supported in bearings 24 carried by rearwardly extending bracket 100 arms 25 of the frame.

The countershaft 23 is provided with a pulley 26 engaging a belt 27 driven by a pulley 28 on the shaft of a motor 29. Obviously, other suitable driving mechanism 105 may be utilized to secure rotation of the crank shaft 19 so that rotary motion thereof is transmitted into an oscillating motion of the drum shaft 9 of the drum 11. This oscillating motion results in a winding and 110 unwinding of the flexible curtain 14 to which the screen 13 is secured. On the pulling

stroke of the drum 11 the screen is drawn in one direction across its chamber and on the reverse stroke the spring drum 12 retracts the slack and pulls the screen 13 in the opposite direction.

The apparatus is designed to operate on a pneumatic principle in which the material to be screened is subjected to a draft or current of air. It has heretofore been proposed to utilize pneumatic means for separation purposes but results therefrom have not been entirely satisfactory for various causes and in the present machine these defects are sought to be overcome by a novel method and construction of devices for effecting the separation.

The material to be screened is carried by suitable means as a bucket conveyor 30 to the upper end of a downwardly and rearwardly inclined feed chute 31 arranged in the front and central portion of the machine. This feed chute terminates in a central pocket 32 disposed vertically and below the lower end of the front panel 6; the upper end of the pocket 32 opening through a mouth 32' into the chamber formed behind the front panel 6 and in front of the screen 13. At the rear of the screen there is provided a back structure consisting substantially of a number of channel shaped strips 33, the flanges of which extend forwardly toward the screen 13 and which flanges are also disposed in comparatively close relation but are spaced sufficiently to form vertically extending channels 34 through which air at atmospheric or increased pressure is designed to pass freely toward the back of the contiguous screen 13. The back members 33 have substantially flat rear walls and the flanges 33' thereof are shown as slightly divergent so that contiguous flanges of the back members 33 form forwardly tapering nozzles of a shape as indicated at 34, Figs. 4 and 5. The back members 33 are arranged with their back webs in a common plane and incline from the top 4 to the bottom 5 of the separating chamber and lie in a position parallel to the screen 13.

It is preferable that the screen 13 be subjected not only to a reciprocating movement in the chamber but also to a vibrating movement to and fro concurrently with the reciprocating motion. Such a vibrating motion may conveniently be produced as by the following means: The back members 33 are shown as connected at their upper ends to a carrying beam 35 and at their lower ends to a carrying beam 36; the back members 33 terminating within the top 4 and the bottom 5 and are, therefore, free to vibrate when actuated by vibrating means. Such means in the illustrated embodiment consists of an electrical apparatus and includes a solenoid core 37 mounted in a spool 38 having an electric winding 39 to receive,

preferably, an alternating electric current having a well known property of causing a core as 37 to reciprocate in the spool. The solenoid is supported in a suitable support including a bar 40 having bearing brackets 41 which may form a portion of the frame. The inner end of the solenoid core 37 is designed to impinge upon a lever 42 which is pivoted at 43 upon a bearing 44 which may extend inwardly from the back bar 40. The lever 42 extends beyond its fulcrum 43 and is connected as by a link 45 to an attachment secured across the backs of the back members 33. Such attachment may consist of transversely disposed angle strips 46 to which the link 45 is pivoted at 47. The lever 42 has connected at one end a contractile spring 48 tending to push the link 45 toward the back members 33 and shift them forwardly and during operation of the solenoid core 37, this hammers upon the lever 42 at a high rate of speed and a slight vibratory motion is, therefore, imparted to the organized or rigidly connected back members 33. It will, therefore, be seen that while the tensioned screen 13 is shifted to and fro across the edges of the nozzle forming flanges 33', these flanges at the same time vibrate slightly with a movement at right angles to the movement of the screen 13, which latter is constantly pressed against the edges of the flanges 33' by a draft of air.

This draft of air is induced as by means of a blower 50 which conveniently may be attached to and driven by the motor 29 and has its suction mouth connected to an upwardly and forwardly inclined throat 51 which terminates at the bottoms of the assembled back members 33, as clearly shown in Fig. 3. The screen 13 is disposed in front of the upper lip or edge of the throat 51 and when the blower is in operation, suction is created in the throat 51 and behind the screen 13, this suction being established in the channels formed in the channel shaped back members 33. The resultant effect is to create suction in the space between the front panel 6 and the screen 13 and this attenuates the air pressure in the feed pocket 32 so that material charged thereto is drawn upwardly into the space behind the panel 6 and is then caused to change its path of travel from an upwardly ascending line to a rearward flow or line of travel wherein it impinges upon the front of the screen 13.

In the ascending chamber behind the front panel 6 is disclosed means consisting of split conduits extending along the front of the screen 13 and registering with the nozzle passage ways 34. By this means there is a differential air pressure maintained at successive zones or areas along the screen 13. These conduits are shown as in the form of flues 53 of triangular cross section with converging rearwardly extending walls spaced

to form, in each flue, a longitudinal orifice 54, and this orifice of each flue is directly opposite the orifice 34 of the back forming members 33. The flues 53 are spaced from 5 the inside surface of the front panel 6 and extend from the top 4 down to the upper end of a discharge spout 55 which may terminate in convergent side walls 56 leading down toward a gravity door or gate 56' which is 10 yieldingly suspended at its upper end over an outlet 55' of the spout 55.

In operation, the motor 29 drives the transmitting mechanism connected to the screen shifting drum 11 and this alternately 15 winds and releases the screen 13 so that this is shifted while supported, substantially on each face, between the nozzle flanges 33' and the flues 53. At the same time the vibrating mechanism including the lever 42 shakes the 20 back structure 33 and this causes the screen 13 to be vibrated to and fro. The blower produces a suction in the throat 30 and in the separating chamber, which draws the material up through the intake mouth 32' from 25 the pocket 32 and the rising material flows upwardly along the front of the screen 13 so that the particles are drawn against the screen in a line substantially perpendicular to its face. The finer material passes 30 through the screen 13 under the effect of the suction in the spaces between the channel members 33 and is drawn down and into the pump from which it is discharged into a conveyor tube 50^a, Fig. 4. The oversize material 35 will accumulate upon the front face of the screen 13. During this accumulation the vibration of the screen causes the layer of material to be loosened so that the material is repeatedly subjected to the suction 40 effect of the draft through the screen, thereby enabling all of the material of a predetermined size to pass through the screen which rejects the oversize. During the vibration of the screen it is shifted with a 45 longitudinal motion on its own length so that zones of the curtain are during operation alternately subjected to the suction effect and also to an atmospheric pressure effect; this latter being obtained as air tends 50 to flow through the several nozzles or spaces 34 into the opposite slit flues 53 which are fixed in the separating chamber as above described. In other words, the layer of accumulated oversize material, and also such 55 fine material as may not have passed through, is constantly being scraped by the opposed nozzle members and shifted into new positions by the shifting of the screen 13 bodily with respect to the atmospheric 60 pressure nozzles. The oversize material being ultimately rejected passes down into the discharge chute 55 where it accumulates behind the gravity gate 56' until such a quantity has been gathered as will over- 65 come the weight of the gate 56' and this

will be swung to an opening position allowing a portion of the accumulated oversize material in the bottom of the chute 55 to flow out immediately after which the gate 56' resumes the normal closed position. Obviously, the discharge action will be intermittent and will continue while the machine is in operation.

From the above it will be seen that by the combined vibrating action and the shifting motion of the screen member 13 the layer of material on the front face thereof will be successively changed in position and the area of the screen will be at certain portions subjected to suction pressure and at 70 intermediate portions to atmospheric pressure and these pressures will be intermittently alternated so that all particles of material will be subjected repeatedly to forces tending to impel them through the screen 13. 85

As the oversize particles are brought into the zones registering with the atmospheric pressure nozzles 34, the oversize material will be subjected to a reverse acting pressure and will be loosened and may freely fall 90 through the discharge flues 53 to the chute 55, this latter and the flues being at atmospheric pressure.

It is obvious that this general principle of operation may be secured, when it is desired, for the treatment of materials to be screened by subjecting them to liquid as well as to air as the impelling agent. In such case, the screen and its coordinate mechanism would, preferably, be arranged in a horizontal 100 plane.

Various modifications and changes may be resorted to within the spirit of the invention as claimed.

What is claimed is:

1. The method of screening fine material, which consists in directing material to be screened in an upward path of movement in air and then changing the direction of movement by a suction effect to impinge it upon 110 an upright screening medium, concurrently reciprocating in the direction of its length and having a vibratory movement to the medium.

2. The method of screening fine material, which consists in directing material to be screened in one path of movement and then changing the direction of movement by a suction effect to impinge it upon a screening medium concurrently reciprocating in the direction of its length and having a vibratory movement to the medium, the vibratory oscillations being at a right angle to the longitudinal movement of the screening medium.

3. The pneumatic method of screening fine material, which consists of directing the material to be screened by and with a current of air against an upstanding screening medium, and alternately present zones of 130

- the medium to different degrees of air pressure.
4. The pneumatic method of screening fine material, which consists of directing the material to be screened by and with a current of air against a screening medium, and alternately present zones of the medium to different degrees of air pressure and in which the differential air pressure is effective in substantially opposite directions.
5. The pneumatic method of screening fine material, which consists of directing the material to be screened by and with a current of air against a screening medium, and alternately present zones of the medium to different degrees of air pressure and in which the differential air pressure is effective in substantially opposite directions, thereby dislodging accumulated layers of the material by the reverse flow of air pressure.
6. The method of screening fine material, which consists in subjecting the material to be screened to a fluid current by which the material is carried to a screening medium, and subjecting the accumulated material on the screening medium to differential degrees of fluid pressure, effective in opposite directions.
7. The method of screening fine material, which consists in subjecting the material to be screened to an upward fluid current by which the material is carried to an oblique screening medium, and subjecting the accumulated material on the screening medium to differential degrees of fluid pressure, the effective pressures being substantially in opposite directions.
8. The method of screening fine material, which consists in subjecting the material to be screened to a fluid current by which the material is carried to an oblique screening medium, subjecting the accumulated material on the lower face of the screening medium to differential degrees of fluid pressure, the effective pressures being substantially in opposite directions, and relatively shifting the effective zones of differential pressure so that zones of the screening area are each alternately subjected to reverse currents, whereby the accumulated layer deposited by one current is agitated and loosened by the action of the reverse current.
9. The method of screening fine material, which consists in subjecting the material to be screened to a fluid current and by which the material is carried to a screening medium, subjecting the accumulated material on the screening medium to differential degrees of fluid pressure, and concurrently subjecting the material on the screen to vibration perpendicular to the plane of the screen.
10. The method of screening fine material, which consists in subjecting the material to be screened to a fluid current by which the material is carried to a screening medium, subjecting the accumulated material on the screening medium to differential degrees of fluid pressure, and effecting a positive dislodgment of a portion of the deposited layer by scraping means.
11. The method of screening fine material, which consists in subjecting the material to the action of a fluid vehicle carrying the material upwardly in an oblique direction from a source of supply, and causing a virtually right angular turn in the direction of the flow of the particles of material so as to impinge them with a perpendicular movement upon the under face of an oblique screening medium.
12. The method of screening fine material, which consists in subjecting the material to the action of a fluid vehicle carrying the material in one direction from a source of supply, causing a virtually right angular turn in the direction of the flow of the particles of material so as to impinge them with a perpendicular movement upon a screening medium, and subjecting the accumulated layer on the screening medium to agitation by fluid pressure acting in a direction reverse to the depositing current.
13. In an apparatus for screening fine material, a screening medium, a supply chamber on one side of the medium and a suction chamber on the opposite side, means for inducing a current flow from the supply chamber to the suction chamber, whereby the material to be screened is drawn from the supply against said medium and the under size material is drawn through the screening medium, means for reciprocating the medium with a longitudinal movement, and means arranged on the receiving side of the medium effective to scrape or dislodge the accumulated layer of over size material and to agitate the same whereby the under size material may be freed to pass through the screening medium.
14. In an apparatus for screening fine material, a screening medium, a supply chamber on one side of the medium and a suction chamber on the opposite side, means for inducing a current flow from the supply chamber to the suction chamber, whereby the material to be screened is drawn from the supply against said medium and the under size material is drawn through the screening medium, means for reciprocating the medium with a longitudinal movement, means arranged on the receiving side of the medium effective to scrape or dislodge the accumulated layer of over size material and to agitate the same whereby the under size material may be freed to pass through the screening medium, said scraping means including tubular discharge flues having longitudinal mouths disposed adjacent the

screening medium, and means for directing a fluid current into each of the discharge flues, whereby to reject the over size material on the screening medium.

5 15. In an apparatus for screening fine material, a screening medium, a supply chamber on one side of the medium and a suction chamber on the opposite side, means for inducing a current flow from the supply 70 chamber to the suction chamber, whereby the material to be screened is drawn from the supply against said medium and the under size material is drawn through the screening medium, means for reciprocating the medium with a longitudinal movement, means arranged on the receiving side of the medium effective to scrape or dislodge the accumulated layer of over size material and to agitate the same whereby the under size 75 material may be freed to pass through the screening medium, said scraping means including tubular discharge flues having longitudinal mouths disposed adjacent the screening medium, means for directing a fluid current into each of the discharge flues, whereby to reject the over size material on the screening medium, and means for vibrating the medium concurrently with its longitudinal reciprocations.

30 16. In a screening apparatus, a screening medium, means for effecting a flow of material to be screened from a supply toward the screening medium and for drawing the under size material through the screening 90 medium, discharge means for the over size material arranged on the supply side of the screening medium, means for longitudinally reciprocating the screening medium, and means for vibrating the screening medium concurrently with its reciprocating movements.

45 17. In a screening apparatus, a screening medium, means for effecting a flow of material to be screened from a supply toward the screening medium and for drawing the under size material through the screening medium, discharge means for the over size material arranged on the supply side of the screening medium, means for longitudinally reciprocating the screening medium, means for vibrating the screening medium concurrently with its reciprocating movements, and means for effecting differential current pressures in zones along the screen, each 100 zone being alternately subjected to the differential pressures during reciprocation so that the collected over size material on the said medium is agitated and dislodged and the under size material freed to pass through.

50 18. In a screening apparatus, a screening medium, means for effecting a flow of material to be screened from a supply toward the screening medium and for drawing the under size material through the screening

medium, discharge means for the over size material arranged on the supply side of the screening medium, means for longitudinally reciprocating the screening medium, means for vibrating the screening medium concurrently with its reciprocating movements, means for effecting differential current pressures in zones along the screen, each zone being alternately subjected to the differential pressures during reciprocation so that the collected over size material on the said medium is agitated and dislodged and the under size material freed to pass through, said discharge means consisting of flues having longitudinal mouths arranged close to the receiving side of the screening medium, and means on the discharge side of the medium disposed contiguous thereto and forming nozzles registering with the said flues, whereby differential pressure is created at the zones of the screening medium alternately presented to the mouths of the discharge flues into which the rejected material is released and thereby discharged.

95 19. In an apparatus for screening fine material, a screening medium, a supply chamber and a suction chamber, means for inducing a current flow from the supply chamber to the suction chamber, whereby the material to be screened is drawn from the supply against said medium and the under size material is drawn through the screening medium, means for reciprocating the medium with a longitudinal movement, and means arranged on the receiving side of the medium effective to scrape or dislodge the accumulated layer of over size material and to agitate the same whereby the under size material may be freed to 105 pass through the screening medium.

100 20. In an apparatus for screening fine material, a screening medium, a supply chamber and a suction chamber, means for inducing a current flow from the supply chamber to the suction chamber, whereby the material to be screened is drawn from the supply against said medium and the under size material is drawn through the screening medium, means for reciprocating the medium with a longitudinal movement, and means arranged on the receiving side of the medium effective to scrape or dislodge the accumulated layer of over size material.

115 21. In an apparatus for screening fine material, a screening medium, a supply chamber and a suction chamber, means for inducing a current flow from the supply chamber to the suction chamber, whereby the material to be screened is drawn from the supply against said medium and the under size material is drawn through the screening medium, means for reciprocating the medium, means arranged on the receiving side of the medium effective to scrape or dislodge the

accumulated layer of over size material, said scraping means including tubular discharge flues having longitudinal mouths disposed adjacent the screening medium, and means for directing a fluid current into each of the discharge flues, whereby to reject the over size material on the screening medium.

22. In an apparatus for screening fine material, a screening medium, a supply chamber on one side of the medium and a suction chamber on the opposite side, means for inducing a current flow from the supply chamber to the suction chamber, whereby the material to be screened is drawn from the supply against said medium and the under size material is drawn through the screening medium, means for reciprocating the medium with a longitudinal movement, means arranged on the receiving side of the medium effective to scrape or dislodge the accumulated layer of over size material and to agitate the same whereby the under size material may be freed to pass through the screening medium, and means for vibrating the medium concurrently with its longitudinal reciprocations.

23. In a screening apparatus, a screening medium, means for effecting a flow of material to be screened from a supply toward the screening medium and for drawing the under size material through the screening medium, discharge means for the over size material, means for longitudinally reciprocating the screening medium, and means for vibrating the screening medium concurrently with its reciprocating movements.

24. In a screening apparatus, a screening medium, means for effecting a flow of material to be screened from a supply toward the screening medium and for drawing the under size material through the screening medium, discharge means for the over size material arranged on the supply side of the screening medium, means for longitudinally reciprocating the screening medium, means for vibrating the screening medium concurrently with its reciprocating movements, and means for effecting differential current pressures in zones along the screen.

25. In a screening apparatus, a screening medium, means for effecting a flow of material to be screened from a supply toward

the screening medium and for drawing the under size material through the screening medium, discharge means for the over size material, means for longitudinally reciprocating the screening medium, means for vibrating the screening medium concurrently with its reciprocating movements, means for effecting differential current pressures in zones along the screen, each zone being alternately subjected to the differential pressures during reciprocation so that the collected over size material on the said medium is agitated and dislodged and the under size material freed to pass through, said discharge means consisting of flues having longitudinal mouths arranged close to the receiving side of the screening medium, and means on the discharge side of the medium disposed contiguous thereto and forming nozzles registering with the said flues, whereby differential pressure is created at the zones of the screening medium alternately presented to the mouths of the discharge flues into which the rejected material is released and thereby discharged.

26. In a screening apparatus, a screening medium, means for effecting a flow of material to be screened from a supply toward the screening medium and for drawing the under size material through the screening medium, discharge means for the over size material, means for longitudinally reciprocating the screening medium, means for vibrating the screening medium concurrently with its reciprocating movements, means for effecting differential current pressures in zones along the screen, each zone being alternately subjected to the differential pressures during reciprocation so that the collected over size material on the said medium is agitated and dislodged and the under size material freed to pass through, said discharge means consisting of flues having longitudinal mouths arranged close to the receiving side of the screening medium, and means on the discharge side of the medium disposed contiguous thereto and forming nozzles registering with the said flues.

In testimony whereof I have signed my name to this specification.

JOHN HERMAN.
